HYDRAULIC BARKING MACHINE

Frank O. White, Edmundston, New Brunswick,
Canada

Application May 19, 1945, Serial No. 594,752

9 Claims. (Cl. 144—208)

1

This invention relates to log barking machines in which jets of fluid are directed against the log to remove the bark and it comprises a machine in which establishment and maintenance of optimum conditions for efficient use of the jets throughout the debarking operation is provided for by appropriate adjustment of the machine to suit the size and shape of the log being debarked.

In its preferred embodiment the invention comprises a log barking machine in which optimum conditions for efficient operation are established and maintained by automatic relative positioning of the nozzles and a log so that, regardless of variations in the size and shape of the log, the nozzles are pointed radially toward the axis of the log and are spaced from the surface of the log a predetermined optimum distance.

A salient feature of this preferred embodiment is the provision of log-controlled mechanism for effecting the aforesaid automatic relative positioning of the nozzles and the log.

Other characteristic features and advantages of the invention will be more readily understood from the following detailed description of the preferred embodiment shown in the accompanying drawings, in which—

Fig. 1 is a plan view of a hydraulic log barking machine embodying my invention.

Fig. 2 is a view partly in elevation and partly in section, the plane of the section being substantially along the line 2—2 of Fig. 1.

Fig. 3 is a sectional view taken substantially along the line 3—3 of Fig. 2.

Fig. 4 is a sectional view taken substantially along the line 4—4 of Fig. 1. This view shows a valve-controlled cylinder and piston device forming part of a nozzle centering means provided for effecting horizontal centering movements of the nozzles shown in the preceding figures.

Fig. 5 is a sectional view of a valve-controlled cylinder and piston device forming part of a second nozzle centering means for effecting vertical centering movements of the nozzles shown in Figs. 1 to 3 inclusive.

Referring more particularly to the drawings, 5 designates a nozzle-supporting ring through which a log 6 is passed by conveyor rolls 7 or other suitable log conveying means. The log is debarked during its travel through ring 5 by high pressure jets of fluid directed against the surface of the log by radial nozzles 8 which are arranged around the path travelled by the log and are slidably supported by ring 5.

2

The direction, velocity and volume of the fluid debarking jets through nozzles 8 and the spacing of the latter from the surface of the log being debarked are important factors to be considered in regard to establishing and maintaining optimum conditions for efficient use of the jets. When the jets are directed radially against the surface of the log they remove the bark by abrasion due to impact and are more efficient than jets which are directed tangentially against the surface of the log to remove the bark by a peeling action. When the jets are directed radially against the surface of the log the number of jets and the consumption of fluid and power required to effect satisfactory removal of the bark is less than when the jets are directed tangentially against the surface of the log. The dryness, thickness of the bark and other characteristics of the log being debarked constitute variable factors which must be taken into consideration in regulating the volume and velocity of the jets to effect economical removal of the bark with minimum removal of the underlying wood. The proper regulation of the jets to take care of these factors can readily be determined by experienced operators.

Experiments have shown that the spacing of the nozzles from the surface of the log must be kept within certain narrow limits to provide the optimum conditions for efficient action of the debarking jets. The optimum spacing selected within these limits is determined in accordance with the character and condition of the logs and other variable factors which can be estimated. One of the important considerations in connection with the relative positioning of the nozzles and log is the use of the minimum number of jets for covering the entire circumference of the largest size log against which the jets are directed and the maintenance of the radial direction of the jets with reference to the surface of the smallest size logs against which the jets are directed.

It will also be understood that, while the described radial direction of the jets against the surface of the log being debarked is preferred, the nozzles 8 may be arranged so that the jets are directed tangentially against the surface of the log. In the latter event the volume and velocity of the fluid jets directed through the nozzles must be increased to give a debarking action equivalent to that obtained when the jets are directed radially against the log.

According to the preferred embodiment of the present invention the foregoing requirements for

efficient operation are met by the provision of log-controlled mechanism which functions automatically to correctly position the nozzles in relation to the surface and axis of the log being debarked. In the machine described herein correct positioning of the nozzles is accomplished partly by automatic centering of the nozzle ring 5 with reference to the log passing therethrough and partly by automatic radial adjustment of the nozzles 8 in relation to the ring and the surface 10 of the log. The centering of the ring in relation to the log ensures that the debarking jets delivered by the nozzles will be directed radially toward the axis of the log while the radial adjustment of the nozzles relative to the ring and log is predetermined to ensure the optimum spacing of the nozzles from the surface of the log. The manner in which these adjustments of ring 5 and nozzles 8 are accomplished will be apparent from the following description.

Ring 5 may be raised or lowered by piston 10 working in cylinder 11 mounted on travelling carriage 12. Piston 10 is attached to piston rod 13 which extends downwardly through stuffing box 14 and carriage cross head 15 to which ring 5 is secured. Working fluid is supplied to the lower end of cylinder 11 by pressure fluid supply pipe 16 which is also connected to a valve chamber 17 provided in a valve casing 18. The upper end of cylinder 11 is connected, by pressure fluid pipe 19, to a second valve chamber 20 provided in valve casing 18. A valve 21 controls communication between chambers 17 and 20 and a second valve 22 controls communication between chamber 20 and an exhaust chamber 23 connected to exhaust line 24. Valves 21 and 22 are spring biased to closed position and are adapted to be alternately opened by a valve operating lever 25 having one end pivoted to valve casing 18 by a pivot 26 affording a pivotal axis about which the lever is swingable in a vertical plane. The pivoted end of lever 25 is provided with a valve opening projection 27 arranged to act against stem 21a of valve 21 and a second valve opening projection 28 arranged to act against stem 22a of valve 22. The opposite end of valve operating lever 25 is connected by link 30 to one arm 31 of a floating bell crank lever 32 which is intermediately pivoted to one end of a valve resetting lever 33 having its opposite end fitted between upper and lower flanges 34 of a lever actuating member 35 carried by cross head 15. Lever 33 is intermediately pivoted to a stationary bracket 36 carried by one of two frame structures 37 supporting track rails 38 on which the wheels 39 of carriage 12 are arranged to run.

Arm 31a of bell crank lever 32 is connected by link 41 to arm 42 extending upwardly from a bracket 43 mounted to swing in a vertical plane about a pivotal axis afforded by hollow trunnions 44 journaled in bearings 45 mounted on frame member 46 forming part of a frame structure 47 through which log 6 is passed.

A log riding control member 48 is intermediately pivoted to bracket 43 by pivot 49 which crosses the pivotal axis of the bracket at right angles thereto. It will thus be seen that bracket 43 and control member 48 are connected together for a unitary swinging movement in a vertical plane about the pivotal axis of the bracket and that member 48 is also capable of an independent lateral or horizontal swinging movement about axis 49 which enables it to follow the contour of a crooked log. The lower end of control member 48 is formed or provided with a substantially V-

shaped log-embracing portion 48' which rests on and rides the surface of the log 6 being debarked.

By virtue of the lever operating linkage provided between valve operating lever 25 and bracket 43 the valves 21 and 22 and piston 10 are automatically operated to cause ring 5 to follow vertical movements of control member 48 resulting from changes in the diameter of the logs ridden by said member. When a larger log is passed under log rider 48 valve operating lever 25 is swung in a counter clockwise direction to open valve 22 so that pressure fluid previously supplied to the upper end of cylinder 11 is exhausted through pipe 19, valve chamber 20, exhaust chamber 23 and exhaust line 24. This permits the pressure fluid acting against the underside of piston 10 to force the piston upwardly and thereby effect an upward centering movement of ring 5. When a smaller log is passed under log rider 48 lever 25 is swung in a clockwise direction to a position in which valve 22 is closed and valve 21 is opened. This allows pressure fluid to pass from supply pipe 16 to the upper end of cylinder 11 to balance the pressure on the two sides of the piston and permit the piston and the ring 5 to be moved downwardly by their own weight.

It is important that ring 5 follow vertical movements of log rider 48 without over-running and this is taken care of in the following manner. During upward movement of ring 5 resetting lever 33 is automatically operated by lever actuating member 35 to lower the pivotal axis of floating bell crank lever 32 and thereby operate link 30 and lever 25 to reset valves 21 and 22 so that upward movement of piston 10 is arrested when ring 5 has moved upwardly a distance corresponding to the upward movement of log rider 48. During downward movement of ring 5 the pivotal axis of floating bell crank lever 32 is automatically raised by resetting lever 33 to operate link 30 and lever 25 to reset valves 21 and 22 to arrest downward movement of piston 10 when ring 5 has travelled downwardly a distance corresponding to the controlling downward movement of log rider 48.

When a crooked log is being debarked a horizontal centering movement of nozzle ring 5 is necessary to maintain nozzles 8 directed radially toward the axis of the log. This is accomplished by operating carriage 12 to cause ring 5 to follow lateral movements imparted to log rider 48 by crooked logs. The carriage shifting mechanism provided for this purpose is automatically controlled by log rider 48 and includes a piston 50 operating in cylinder 51 and connected to carriage 12 by piston rod 52. One end of cylinder 51 is connected by pipe 54 to a pressure fluid chamber 55 provided in valve casing 56. A valve 57 controls communication between chamber 55 and exhaust chamber 58 connected to exhaust line 59. A second valve 60 controls communication between chamber 55 and pressure fluid inlet chamber 61 connected to pressure fluid supply line 62. The opposite end of cylinder 51 is connected, by pipe 64, to fluid distributing chamber 65 provided in valve casing 66. A valve 67 controls communication between chamber 65 and an exhaust chamber 68 connected to exhaust line 69. A valve 70 controls communication between chamber 65 and a pressure fluid inlet chamber 71 connected to pressure fluid supply pipe 72.

Valves 57, 60, 67 and 70 are biased to closed position by the valve closing springs shown associated therewith.

A vertically disposed valve operating lever 74

is pivotally secured to supporting bracket 15 by pivot 76 located near the upper end of the lever. Bracket 15 is shown connecting valve casings 56 and 66 which are spaced apart to receive there-between the upper end of lever 74.

Lever 74 is formed to provide a valve opening part 78 extending above the pivot 76 and a second valve opening part 79 located immediately below said pivot. Valve opening part 78 is arranged to act alternately against stems 57a and 67a of valves 57 and 67 while valve opening part 79 is arranged to act alternately against stems 60a and 70a of valves 60 and 70.

The lower end of valve operating lever 74 is connected by link 81 to the lower end of a lever 82 intermediately pivoted to a valve operating slide 83 working in bearings 84 mounted on one of the carriage rails 38. The upper end of lever 82 is connected to carriage 12 by a valve resetting link 85 which is pivoted at one end to the lever 82 and likewise pivoted at the other end to the carriage 12. Flexible slide operating elements 86 and 86' are connected between the opposite ends of slide 83 and the upper extremity of log rider 48. These flexible elements pass through the hollow trunnions 44 of bracket 43 and are trained around suitable guide pulleys 87 carried by frame structures 37 and 47.

When log rider 48, as viewed in Fig. 1, is moved in the direction indicated by arrow X by a crooked log, the valve operating slide 83, the lower end of lever 82, the link 81 and the lower end of valve operating lever 74 are also moved in the same direction by the pull of the flexible element 86 connected between the slide and the upper extremity of log rider 48. The valve operating lever 74 (Fig. 4) is thus swung about pivot 76 so that valve operating part 78 is moved against stem 67a to open valve 67 while valve operating part 79 is simultaneously moved against stem 60a to open valve 60. The opening of valve 67 permits pressure fluid previously supplied to the left hand end of cylinder 51 to be exhausted by way of pipe 64, valve chamber 65, exhaust chamber 68 and exhaust line 69. The opening of valve 60 permits pressure fluid to pass from fluid supply pipe 62 to the right hand end of cylinder 51 by way of valve chambers 61 and 55 and pipe 54. Piston 50 and the connected carriage 12 are thus moved to the left to effect a corresponding movement of ring 5.

When log rider 48 is moved in the direction indicated by arrow X' (Fig. 1) by a crooked log, the slide 83, the lower end of lever 82, the link 81 and the lower end of valve operating lever 74 are also moved in the same direction by the pull of the flexible element 86'. Valve operating lever 74 is thus swung about its pivotal axis 76 so that valve opening part 78 is moved against stem 57a to open valve 57 while valve opening part 79 is simultaneously moved against stem 70a to open valve 70. The opening of valve 57 permits the pressure fluid previously supplied to the right hand end of cylinder 51 to be exhausted therefrom by way of pipe 54, valve chambers 55 and 58 and exhaust line 59. The opening of valve 70 permits pressure fluid to pass from pressure fluid supply pipe 72 to the left hand end of cylinder 51 by way of valve chambers 71 and 65 and pipe 64. This results in piston 50 and carriage 12 being shifted to the right to effect a corresponding movement of ring 5.

Overrunning of ring 5 in either direction during horizontal centering movement thereof is prevented by the action of valve resetting

link 85 working through lever 82 and link 81. As it moves with carriage 12 link 85 swings the lower end of lever 82 in a direction opposite to the direction of travel of the carriage so that through the agency of link 81, valve operating lever 74 is operated to a position in which the valves previously opened by said lever are permitted to close to thereby arrest the motion of piston 50 and carriage 12 when ring 5 has been moved horizontally in the same direction and to the same extent as the log rider 48.

Nozzles 8 are automatically positioned a predetermined fixed distance from log 6 by nozzle-adjusting mechanism operating in response to vertical centering movement of ring 5 in relation to carriage 12. This nozzle-adjusting mechanism includes bell-crank 97 intermediately pivoted to brackets 98 mounted on the outer peripheral portion of ring 5. Arm 99 of each bell-crank 97 is pivotally connected to the outer end portion of one of the nozzles 8. The remaining arms 100 of bell-crank 97 are interconnected by link 101 to provide for simultaneous operation of said bell-crank by two main operating links 102, each having one end pivotally connected to one of the bell-crank arms 100 and the other end pivotally connected to carriage 12. Bell-crank 97 and links 101 and 102 are designed to shift the nozzles radially toward or away from the surface of the log in response to vertical centering movements of ring 5 relative to carriage 12, the extent and direction of radial movement of the nozzles being predetermined to maintain a fixed distance between the nozzles and the log for any centered position of ring 5.

The nozzles 8 may be of any suitable design. They extend radially through ring 5 and slide in suitable guide openings 104 so that their delivery ends are always pointed toward the axis of the ring. Their outer ends are connected by flexible pipes 105 to water supply conduit 106 to which water is delivered under suitable pressure from a pumping system or other source.

The nozzles 8 are shown lying in a common plane but they may be staggered so that each nozzle is offset in the axial direction of the ring with reference to the next adjacent nozzle. With proper spacing the staggered arrangement of the nozzles enables the entire circumference of the log to be covered by the jets without interference of the jets with each other.

While not shown in the drawings it will readily be understood that suitable control valves or other means may be provided to regulate the pressure and volume of the jets delivered through the nozzles in accordance with the diameter, dryness and other conditions of the log being debarked.

In some instances it may be advantageous to employ combined air and water nozzles through which jets of air as well as jets of water are directed against the log. In such cases the air may be delivered by each nozzle as an annular jet enveloping and confining a central water jet to prevent excessive spreading of the latter. Sand or other abrasive materials may also be supplied to the nozzles to be entrained by the air and/or water jets.

In reviewing the complete operation of the hydraulic barking machine described herein it may be noted that the log riding member 48 constitutes a vertically and laterally movable feeler whose vertical movements are determined by the diameter of the log passing therebeneath

and whose lateral movements are determined by the lateral crookedness of the engaging log. The vertical movements of member 48 are transmitted through bracket 43 and the associated valve operating linkage to operate the previously described valve mechanism through which pressure fluid is routed to and from cylinder 11 to effect corresponding vertical movements of piston 10 and nozzle ring 5. Lateral movements of member 48, due to crookedness of the engaging log, are transmitted through flexible elements 86 and 86' to operate the previously described valve mechanism through which pressure fluid is routed to and from cylinder 51 to effect corresponding movements of carriage 12 and ring 5 in the lateral direction of the log.

From the foregoing description it will be seen that the vertical centering movements of nozzle ring 5 with respect to the log are determined by the diameter of the log and that the lateral centering movements of ring 5 with respect to the log are determined by the lateral crookedness of the log and that these movements of the ring are effected by mechanisms controlled by movement of the log actuated feeler 48.

During vertical centering movements of ring 5 relative to the log and the ring supporting carriage 12, the nozzle adjusting mechanism comprising bell cranks 97 and links 100, 101 and 102, functions to shift the nozzles 8 radially in relation to the center of said ring to maintain the predetermined spacing of the delivery ends of the nozzles from the surface of the log.

Having thus described the nature of my invention and a preferred embodiment thereof, it will be understood that various modifications may be resorted to within the scope and spirit of the invention as defined by the appended claims. For example, various means other than the specific means described herein may be employed for effecting the necessary adjustments of the nozzle ring 5 and the nozzles 8.

I claim:

1. A log debarking machine comprising, a support, a nozzle carrier provided with a central opening through which a log to be debarked is passed lengthwise, a plurality of nozzles movably mounted on said carrier and normally converging toward the center of said carrier opening, said carrier being mounted on said support for selective vertical and transverse movements in its own plane and with respect to the longitudinal axis of said log, independent means for imparting said vertical and transverse movements to said carrier, means responsive to the vertical movement of said carrier for moving said nozzles toward and away from the center of said carrier opening, and means responsive to the shape of the log to selectively actuate said carrier movement imparting means.

2. A log debarking machine comprising, a support, a nozzle carrier provided with a central opening through which a log to be debarked is passed lengthwise, a plurality of nozzles movably mounted on said carrier and normally converging toward the center of said carrier opening, said carrier being mounted on said support for selective vertical and transverse movements in its own plane and with respect to the longitudinal axis of said log, means for imparting said movements to said carrier, means responsive to the vertical movement of said carrier for moving said nozzles toward and away from the center of said carrier opening, and a log-actuated control mechanism operatively connected to said carrier movement

imparting means to selectively actuate said movement imparting means.

3. A log debarking machine comprising, a support, a nozzle carrier mounted on said support and provided with a central opening through which the log to be debarked is passed lengthwise, a plurality of nozzles movably mounted on said carrier and normally converging toward the center of said carrier opening, a carriage movable on said support transverse the longitudinal axis of said log, means for imparting transverse movements to said carriage, means mounted on said carriage having attachment with the nozzle carrier and operable to impart vertical movement to said carriage, means responsive to the vertical movement of said carrier for moving said nozzles toward and away from the center of said carrier opening, and means controlled by the shape of the log to selectively actuate said carrier transverse and vertical movement imparting means.

4. A log debarking machine comprising, a support, a nozzle carrier mounted on said support and provided with a central opening through which a log to be debarked is passed lengthwise, a plurality of nozzles movably mounted on said carrier and normally converging toward the center of said carrier opening, a carriage movable on said support transverse the longitudinal axis of said log, means for imparting transverse movements to said carriage, means mounted on said carriage having attachment with the nozzle carrier and operable to impart vertical movement to said carriage, means responsive to the vertical movement of said carrier for moving said nozzles toward and away from the center of said carrier opening, and log-actuated control means for selectively actuating said carrier transverse and vertical movement imparting means.

5. A log debarking machine comprising, a support, a nozzle carrier mounted on said support and provided with a central opening through which a log to be debarked is passed lengthwise, a plurality of nozzles movably mounted on said carrier and normally converging radially toward the center of said carrier opening, a carriage movable on said support transverse the longitudinal axis of the log to be debarked, power means for effecting transverse movement of said carriage, a power means mounted on said carriage having attachment with said nozzle carrier and operable to effect vertical movement of said nozzle carrier, means responsive to the vertical movement of said carrier for moving said nozzles toward and away from the center of said carrier opening, and log actuated control means to selectively actuate said power means.

6. A log debarking machine comprising, a support, a nozzle carrier mounted on said support and provided with a central opening through which a log to be debarked is passed lengthwise, a plurality of nozzles movably mounted on said carrier and normally converging toward the center of said carrier opening, a carriage movable on said support transverse the longitudinal axis of the log to be debarked, power means for effecting transverse movements of said carriage, a power means mounted on said carriage having attachment with said nozzle carrier and operable to effect vertical movement of said nozzle carrier, means responsive to the vertical movement of said carrier for moving said nozzles toward and away from the center of said carrier opening, and a log-actuated control mechanism having operable connections with said power means to selectively impart vertical and transverse movements to said carrier.

7. A log debarking machine comprising, a support frame, a nozzle carrier mounted on said support frame and provided with a central opening through which a log to be debarked is passed lengthwise, a plurality of nozzles movably mounted on said carrier and normally converging toward the center of said carrier opening, a carriage movable on said frame transverse the longitudinal axis of the log to be debarked, power means for effecting movements of said carriage, valve mechanism for operating said power means, a power lift mounted on said carriage and having connection with the carrier and operable to effect vertical movement of the carrier, valve mechanism for operating the power lift, linkage between the carriage and the carrier and nozzles responsive to movements of said carrier to move said nozzles toward and away from the center of said carrier opening, and means to selectively control and actuate the power means valve mechanism.

8. A log debarking machine comprising, a support frame, a nozzle carrier mounted on said support frame and provided with a central opening through which a log to be debarked is passed lengthwise, a plurality of nozzles movably mounted on said carrier and normally converging radially toward the center of said carrier opening, a carriage movable on said frame transverse the axis of the log to be debarked, power means for effecting movement of said carriage, valve mechanism for operating said power means, a power lift mounted on said carriage and having connection with the carrier and operable to effect vertical movement of the carrier, valve mechanism for operating the power lift, linkage between the carriage and the carrier and nozzles responsive to the vertical movement of said carrier for moving said nozzles toward and away from the center of said carrier opening, and a log-actuated

control mechanism having operable connections with said valve mechanisms to selectively impart vertical and horizontal movements to the nozzle carrier.

5 9. A log debarking machine comprising, a support, a nozzle carrier provided with a central opening through which a log to be debarked is passed lengthwise, a plurality of nozzles movably mounted on said carrier and normally converging toward the center of said carrier opening, said carrier being mounted on said support for selective vertical movements in its own plane and with respect to the longitudinal axis of said log, means for imparting said vertical movements to said carrier, means responsive to the vertical movement of said carrier for moving said nozzles toward and away from the center of said carrier opening, and means responsive to the shape of the log to selectively actuate said carrier movement imparting means.
